GYRATORY CRUSHER HAVING A FLOATING RING

Samuel W. Traylor, Jr., Allentown, Pa.

Application January 24, 1946, Serial No. 643,033

18 Claims. (Cl. 241—140)

1.

The present application is a continuation-in-part of applicant's prior application, Serial No. 589,877, filed April 23, 1945, now abandoned.

This invention relates to crushers of the upright gyratory type and has as an object to greatly increase the capacity of such crushers by providing them with a plurality of crushing spaces, this object being attained by the provision of a floating ring in the space between inner and outer crushing members so that a free-discharging crushing space is caused to exist at each side of the ring during normal operation. Another object is to provide means whereby undue cocking of the ring, such as might cause jamming between the crushing members, is prevented. Another object is to provide a multi-space gyratory crusher designed to eliminate choking in the crushing spaces, this being accomplished by shaping the opposed crushing faces so that each crushing space, which is downwardly tapering, is divided into a succession of superposed zones of which each has a volumetric capacity sufficient to receive all of the material reaching it from the next higher zone.

The invention is shown in practical embodiment, by way of example, in the accompanying drawings, in which.

Figure 1 is a partial axial section of a crusher embodying a floating crushing ring.

Figure 2 is an enlargement of a portion of Figure 1.

Figure 3 is a partial axial section of another embodiment illustrating means for preventing undue cocking of the ring.

Figure 4 is a section on line 4—4 of Figure 3.

Figure 5 is a partial axial section of a crusher showing another form of ring restraining means.

Figure 6 is a partial plan view of the ring of Figure 5.

Figure 7 is a partial axial section of a crusher showing a further form of ring restraining means, and

Figure 8 is a section on line 8—8 of Figure 7.

In Figure 1, reference numeral 5 designates a frame or casing shown as comprising upper and lower portions 6 and 7 which support between them a horizontally disposed crushing member in the form of a concave 8 having an annular crushing face 9 which tapers upwardly and is somewhat convexly curved. Above the concave 50 is a feed chamber 10 and below it is a discharge chamber 11.

Reference numeral 12 designates a gyratory shaft whose upper end is supported in a bearing 13 provided by frame portion 6 and whose lower end is supported in an eccentric bushing whereby gyratory movement is imparted to the shaft. This mechanism may be conventional and, hence, is not illustrated. In this connection, reference may be had to the prior art as exemplified, for

2.

example, in the patent to Richard Bernhard, No. 1,837,102 of Dec. 15, 1931. Wedged on an upwardly tapering conical portion 14 of shaft 12 and retained by means of a spacer sleeve 15 and nut 16, is a crushing member in the form of a head 17 within the concave 8. Head 17 has an upwardly tapering conical crushing surface 18 which tapers upwardly less steeply than the crushing face 9 of the concave element 8 and which, with face 9 of the concave, defines an annular space 19 of downwardly tapering section.

Disposed in the space 19 is a ring 20 which has upwardly tapering outer and inner faces 21 and 22, respectively opposed to faces 9 and 18. As here shown, the face 21 is conical while the face 22 is convexly curved from top to bottom. It will be noted that the outer face 21 tapers upwardly less steeply than the opposed inner face 9 of the concave and that the inner face 22 of the ring tapers upwardly more steeply than the opposed outer face 18 of the head 17. Moreover, the inner and outer surfaces of the ring converge upwardly so that the ring is of upwardly tapering thickness in axial section.

When the crusher is at rest and empty, ring 20 rests directly on head 17. However, when material to be crushed, such as rock, is fed through the passage 10 with the crusher driven so that head 17 is gyrating, the ring immediately assumes a substantially level position substantially midway between surfaces 9 and 18 and retains this position during normal operation so that two upwardly enlarging crushing spaces designated 23 and 24, Figure 2, are caused to exist. The ring normally tends to move with the head and a majority of the crushing is normally done on the outside of the ring. The increased capacity of the crusher is due to the crushing accomplished on the inside of the ring. This increased capacity is normally from 25% to 35% and over.

In conventional crushers, when the opening on the closed side is small with respect to the throw, excessive power is consumed due to the choking action of the material being crushed. With the new arrangement, however, when the pressure on the outside of the ring becomes excessive, the head can move and as it moves it crushes material on the inside so that excessive power requirements are avoided. Crushing is accomplished through a cushion of crushable material. Should a piece of tramp iron or other uncrushable substance be introduced, say in the outer crushing space 23, the head will be moved relative to the ring against the material in space 24, thereby relieving excessive strain and, at the same time, crushing material in the latter space.

The open relation of the parts is shown at the left in Figure 1 and in Figure 2, and the closed relation at the right in Figure 1. In Figure 1 it

will be seen that the ring is slightly canted to the left to give a self-adjustment of the crushing spaces with the ring substantially midway between the faces of the concave end head.

Referring to Figure 2, the crushing action in space 23 is assumed to start at about the line *x* and faces 9 and 21 are in normal maximum spaced apart relation. The shape of faces 9 and 21 is such that the distance between them in the maximum closed relation will be substantially equal to that portion of the line *y* which is between the faces. Consequently, a piece of material which is engaged on the line *x* when the jaws are apart can be crushed to a size enabling it to drop to the line *y* when the faces 9 and 21 again move apart. The length of line *z* between the faces is substantially equal to the distance between the faces along the line *y* when they are in closed relation. Hence, a piece of material caught on the line *y* in the open relation can be crushed so as to fall to the line *z* when the faces again move apart. The volume of the annular zone between lines *y* and *z* is not less than the volume of the annular zone between lines *x* and *y* and, consequently, all of the material crushed in the latter zone is receivable in the former so that choking cannot occur. The same principles apply with respect to the zone of space 23 which is below line *z*. The same zone divisions are present in the space 23 as indicated by the lines *x'*, *y'* and *z'*. It will be understood that the described zone relationship may be temporarily upset when uncrushable material is encountered, but the relationship is substantially maintained during normal operation. Due to the fact that the ring, as shown, floats during normal operation, and is hence subjected to no positive restraint in any direction by fixed connections, it is fully self-adjusting in the material resulting in an improved mode of operation.

As above stated, in normal operation, the ring retains a more or less level position with no jamming tendency. However, when the crusher is running empty, or is receiving initial feed, or when it is not getting sufficient feed to keep it comparatively full, the ring has a tendency to cock, sometimes cocking so badly as to jam. This difficulty can be overcome in a number of ways as will now be explained.

Referring to Figure 3, the frame portion 30 of the crusher carries the concave 31 and through arms as at 32, of which there are usually three, supports a bearing 33 for the upper end of the gyratory shaft 34, the bearing being equipped with a cap 35.

The crushing head 36 comprises a core portion 37 wedged on an upwardly tapering portion 38 of shaft 34 and, in turn, having wedged thereon a mantle 39 retained by means of a nut 40 threaded on the shaft. An annular crushing space, which enlarges upwardly, is defined between the upwardly curvilinearly tapering convex face 41 of the concave and the upwardly curvilinearly tapering concave face 42 of the mantle 39.

Disposed in the space between the head and concave is a ring 43 which has an upwardly tapering concaved outer face 44 and an upwardly tapered convexed inner face 45 so that upwardly enlarging outer and inner spaces are provided between the ring and the concave and the ring and the head, respectively. With the machine empty, the ring rests on the head.

It should be noted that the relationship between the steepness of taper of the four crushing

surfaces is generally the same as in the first form of the invention. That is to say, the inner face 41 of the concave tapers upwardly more steeply than the opposed outer face 44 of the ring, and the inner face 45 of the ring tapers upwardly more steeply than the opposed outer face 42 of the head, thereby providing two annular, downwardly tapering crushing spaces. The inner and outer surfaces of the ring converge upwardly so that the ring is of upwardly tapering thickness in axial section.

I have found that if the material to be crushed is initially fed to the inner crushing space only, jamming will not occur. After the inner space is filled, the material will overflow into the outer crushing space, but until such overflow occurs, the ring moves with the head and no crushing action takes place. Therefore, the invention contemplates arrangements by which the material will substantially all be fed into the inner space so that, when starting up, undue cocking of the ring will be avoided.

To this end, I may provide a hopper in the form of an upright cylinder 50 having cut-outs as at 51 in its lower portion for the reception of the arms as at 32, the upper edge of the cut-outs supporting the hopper on the arms and the diameter of the hopper being such as to give substantial clearance around the bearing 33 and cap 35. Reference numeral 52 designates a circular plate supported above cap 35 in spaced relation to the inner walls of the cylinder by means of brackets as at 53. Reference numeral 54 designates an annular ledge at the lower end of cylinder 50 and defining a discharge opening 55 whose diameter is about that of the upper inner edge of ring 33. Material fed onto plate 52 falls through the hopper around the bearing and cap, builds up on ledge 54, and then drops into the space between the ring and head. After this space is filled, the material will overflow into the outer space between the ring and the concave and crushing action will begin.

In Figures 3 and 4 reference numeral 56 designates lugs projecting radially from nut 40 and having lower edges spaced above the normal operating level of the top edge of the ring. Undue cocking of the ring is prevented by its engagement with one or more of the lugs.

Also, in Figure 4, the mantle is shown as being provided with outwardly projecting lugs 57 adjacent the top of the ring with their outer ends sufficiently spaced from the inner surface of the ring so as not to interfere with the normal movement of the ring during crushing. However, one or more of the lugs 57 will engage the inner surface of the ring to prevent undue cocking thereof.

All of the described anti-cocking provisions, i. e., the hopper, the lugs 56, and the lugs 57, may be used together, or they may be used singly.

In Figure 5, the ring 43' is provided with inwardly projecting lugs 58 of which there may be three in equally spaced relation, these terminating sufficiently short of the mantle so as not to interfere with normal movement of the ring but serving, in the same manner as lugs 57 of Figures 3 and 4, to prevent undue cocking of the ring.

Referring to Figures 7 and 8, the head 59 terminates upwardly in a shoulder engaged by a spacer sleeve 60 provided with an annular rib 61 so that an annular channel 62 is provided. Received in the channel is a loose fitting collar 63 whose inner surface is axially convexed so that the collar is universally tiltable, and it is also freely axially movable in the channel. The collar

is connected with the upper part of a crushing ring 64 through arms 65 between which spaces exist through which material to be crushed can be fed to the inner upwardly enlarging crushing space. When the machine is empty, ring 64 is supported by the head. Any undue cocking of the ring is prevented by the collar 63 although it floats freely in normal operation.

Variations in the form and arrangement of parts are possible and contemplated under the invention as defined in the following claims.

I claim:

1. A gyratory crusher comprising inner and outer cooperating crushing members of which the inner is gyratory on an upright axis, said members having upwardly tapering opposed crushing faces defining an annular space, and a floating ring in said space having upwardly tapering and upwardly converging inner and outer faces which in the normal operation of the crusher define inner and outer downwardly tapering crushing spaces with the faces of said inner and outer members respectively, the inner face of said ring overlying the face of said inner member so as to be supported thereby along a circular, substantially line contact adjacent the lower end of said inner face when the space between the two faces is empty and when the ring is level, said ring being tiltable both upwardly and downwardly at all points around its circumference both when said spaces are empty and when having material therein.

2. A gyratory crusher comprising a gyratory head arranged on an upright axis and having an annular upwardly tapering crushing face, a concave surrounding said head and having an annular upwardly tapering crushing face, said faces defining an annular space between them, and a floating ring of upwardly tapering thickness in axial section in said space having upwardly tapering inner and outer faces which in the normal operation of the crusher define annular inner and outer downwardly tapering crushing spaces with the faces of the head and concave respectively, said ring being supported through contact with the head along a substantially line contact when said inner crushing space is empty and being supported by the material when said inner space contains material to be crushed, said ring being tiltable both upwardly and downwardly at all points around its circumference both when said spaces are empty and when having material therein.

3. A gyratory crusher comprising inner and outer cooperating crushing members of which the inner is gyratory on an upright axis, said members having upwardly tapering opposed crushing faces defining an annular space, a floating ring in said space having upwardly tapering and upwardly converging inner and outer faces defining inner and outer downwardly tapering crushing spaces with the faces of said inner and outer members respectively, and means for directing material to be crushed substantially exclusively to the top of said inner space, said ring being supported by the crushing face of the inner member when the inner crushing space is empty and being tiltable upwardly and downwardly at all points around its circumference when said space is empty and when full.

4. A gyratory crusher comprising inner and outer cooperating crushing members of which the inner is gyratory on an upright axis, said members having upwardly tapering opposed crushing faces defining an annular space, a float-

ing ring in said space having upwardly tapering and upwardly converging inner and outer faces defining inner and outer downwardly tapering crushing spaces with the faces of said inner and outer members respectively, and a hopper for the material to be crushed above said crushing members and ring having a bottom opening above said inner space and of such size as to deliver the material substantially exclusively to said inner space.

5. A gyratory crusher comprising inner and outer cooperating crushing members of which the inner is gyratory on an upright axis, said members having upwardly tapering opposed crushing faces defining an annular space, a floating ring in said space having upwardly tapering and upwardly converging inner and outer faces defining inner and outer downwardly tapering crushing spaces with the faces of said inner and outer members respectively, said ring being supported by the crushing face of the inner member when the annular space is empty and being tiltable upwardly and downwardly at all points along its circumference when said space is empty and when full, and stop means preventing undue tilting of said ring in said annular space.

6. A gyratory crusher comprising inner and outer cooperating crushing members of which the inner is gyratory on an upright axis, said members having upwardly tapering opposed crushing faces defining an annular space, a floating ring in said space having upwardly tapering and upwardly converging inner and outer faces defining inner and outer downwardly tapering crushing spaces with the faces of said inner and outer members respectively, and lugs in fixed association with one of said crushing members projecting above said ring to limit the cocking thereof in said annular space.

7. A gyratory crusher comprising inner and outer cooperating crushing members of which the inner is gyratory on an upright axis, said members having upwardly tapering opposed crushing faces defining an annular space, a floating ring in said space having upwardly tapering and upwardly converging inner and outer faces defining inner and outer downwardly tapering crushing spaces with the faces of said inner and outer members respectively, and outwardly projecting lugs on said inner member engageable by the upper portion of said ring to limit cocking of said ring in said annular space.

8. A gyratory crusher comprising inner and outer cooperating crushing members of which the inner is gyratory on an upright axis, said members having upwardly tapering opposed crushing faces defining an annular space, a floating ring in said space having upwardly tapering and upwardly converging inner and outer faces defining inner and outer downwardly tapering crushing spaces with the faces of said inner and outer members respectively, and lugs projecting radially from the upper end of said ring engageable with one of said members to limit cocking of said ring in said annular space.

9. A gyratory crusher comprising inner and outer cooperating crushing members of which the inner is gyratory on an upright axis, said members having upwardly tapering opposed crushing faces defining an annular space, a floating ring in said space having upwardly tapering inner and outer faces defining inner and outer downwardly tapering and upwardly converging crushing spaces with the faces of said inner and outer members respectively, a collar

longitudinally slideable and universally tiltable on the axis of said inner member, and spaced apart arms connecting the upper portion of said ring with said collar.

10. A gyratory crusher comprising a gyratory head and a concave supported in surrounding relation to the head, said head and concave having opposed faces defining an annular crushing space between them, and a floating ring of upwardly decreasing thickness in axial section in said space dividing the latter into inner and outer spaces, said head having a portion which supports said ring when said inner space is empty, the ring having an inner face so shaped with respect to the face of the head that said inner space in the empty condition is upwardly divergent, to facilitate the entry of material to be crushed into said inner space, to lift the ring from direct contact with the head, said ring, in the normal operation of the crusher being tiltable both upwardly and downwardly to facilitate passage of non-crushable objects through said inner and outer spaces.

11. A gyratory crusher comprising a gyratory head and a concave supported in surrounding relation to the head, said head and concave having opposed faces defining an annular crushing space between them, a floating ring of upwardly decreasing thickness in axial section in said space dividing the latter into inner and outer spaces, said inner member having a portion which supports said ring when said inner space is empty, the ring having an inner face so shaped with respect to the face of the head that said inner space in the empty condition is upwardly divergent, and a hopper arranged to feed material to be crushed substantially only to said inner space.

12. A gyratory crusher comprising a gyratory head arranged on an upright axis and having an annular upwardly tapering crushing face, a concave surrounding said head and having an annular upwardly tapering crushing face, said faces defining an annular space between them, a floating ring in said space and supported through contact with said head when said space is empty, said ring having upwardly tapering and upwardly converging inner and outer faces which in the normal operation of the crusher define annular upwardly enlarging inner and outer crushing spaces with the faces of the head and concave respectively, and a hopper arranged to feed material to be crushed substantially only to said inner space.

13. A gyratory crusher comprising a head gyratory on an upright axis, a concave surrounding the head, the head and concave having opposed crushing faces defining a downwardly tapering annular space therebetween, and a floating ring in said space having inner and outer upwardly converging surfaces opposed to the faces of the head and concave, providing inner and outer crushing spaces which taper downwardly in vertical section, the crushing face of the head being extended under the inner surface of the ring in direct supporting relation thereto along a circular, substantially line contact when the inner crushing space is empty and when the ring is level, the ring being normally supported substantially midway between the head and concave by the material being crushed, and being tiltable upwardly and downwardly at all points around its circumference when the

inner space is empty and when the same contains material to be crushed.

14. A crusher in accordance with claim 13, characterized in that the floating ring is of upwardly tapering thickness in axial section.

15. A crusher in accordance with claim 13, characterized in that the inner surface of the floating ring in axial section is convexly curved and in that the ring is of upwardly decreasing thickness in axial section.

16. A crusher in accordance with claim 13, characterized in that the floating ring has, in axial section, a concave outer surface and a convex inner surface providing an upwardly tapering ring thickness in said section.

17. A gyratory crusher comprising a normally stationary concave element having an upwardly tapering inner annular face which is convex in axial section, a head within the concave gyratory

20 on an upright axis having an upwardly tapering outer annular face which is concave in axial section, said faces providing a downwardly tapering annular space therebetween, and a floating ring in said space above the head having an outer surface which is concave in axial section,

25 facing the inner face of said concave element and an inner surface which is convex in axial section, facing the outer face of the head, said ring being of upwardly tapering thickness in axial section and providing inner and outer

30 downwardly tapering crushing spaces between its surfaces and the faces of the head and concave, respectively, said ring being normally supported between the head and concave by the material

35 being crushed and being supported, when the inner crushing space is empty, by direct contact with the outer face of the head, the ring being tiltable upwardly and downwardly at all points around its circumference when the inner crushing space is either empty or contains material to be crushed.

40 18. A gyratory crusher comprising a normally stationary concave element having an annular, upwardly tapering, inner face, a gyratory head

45 within the concave having an annular outer face tapering upwardly less steeply than said annular inner face, said faces providing a downwardly tapering annular space therebetween, and a floating ring in said space having an outer sur-

50 face which tapers upwardly less steeply than the inner surface of the concave element and an inner surface above the outer face of the head and which tapers upwardly more steeply than the latter, the ring being supported by the outer

55 face of the head for free tilting movement both upwardly and downwardly when the crusher is empty and when full.
